UNITED STATES PATENT OFFICE

GEORGE M. SVOJSE, OF CHICAGO, ILLINOIS

GARMENT PRESSING MACHINE

Application filed March 15, 1929. Serial No. 347,370.

My invention relates to the conventional types of garment pressing machines employing steam under pressure, and more particularly to the control of steam applied to the upper buck of the pressing machine, and my main object is to secure the delivery of steam to the buck by simply forcing the garment against the same for pressing.

5 A further object of the invention is to secure the steam delivery by imparting a movement to the upper buck which opens the steam valve.

10 15 A still further object of the invention is to enable both hands to be used for properly holding and pressing the garment, and to deliver steam to the latter without removing either hand from the garment or actuating any separate control.

20 Another object of the invention is to provide a novel bracket for use in conjunction with the conventional type of pressing machine, whereby to secure the steam delivery automatically.

25 A significant object of the invention is to provide a peculiar adjunct to the mechanism of the upper buck of the pressing machine which will always place the buck in position for immediate use in accordance with my invention.

30 An additional object of the invention is to construct the novel bracket with means for folding into a compact body or in a position of non-use.

35 A final, but nevertheless important object of the invention is to design the novel bracket in the manner of an attachment of exceeding simplicity and to position the same where it will in no manner hinder the general operation of the machine.

40 With the above objects in view and any others that may suggest themselves from the specification and claims to follow, a better understanding of the invention may be had 45 to reference to the accompanying drawings, in which—

Figure 1 is a side elevation of a typical garment pressing machine, showing the application of my invention, partly in section;

50 Fig. 2 is a group perspective view of parts

entering into the assembly of my invention; and

Fig. 3 is an enlarged section on the line 3—3 of Figure 1.

In the use of the standard type of garment pressing machine, the main features involved are, according to the drawings, the lower buck 5, the upper buck 6, the rocker frame 7 for the latter, the base 8 for the rocker frame and the bumper 9. For ordinary pressing, 55 the garment is laid upon the lower buck 5 and the upper buck depressed by means of a handle 6a to close upon the garment, the lever 10 of the steam valve 11 then being pressed down with one of the hands to deliver steam 60 to the upper buck. However, where only portions of a garment are to be pressed, such as shoulders, sleeves or other parts which cannot conveniently be laid upon the lower buck, the practise is to mount the part to be pressed 65 upon the open hand of the operator and to apply the same directly against the poised upper buck. While this is done with one hand, the other hand reaches over the buck 70 to press down the lever 10 for the supply of steam. This method of pressing garment parts is undesirable in some respects. First, only a small area of the part to be pressed can be applied, or so much as covers the hand; second, the hand reaching over the buck to 75 apply the lever 10 is subjected to the general rush of steam from the buck and is scalded unless the hand is quickly removed or the arm jacketed to shield it from the steam. Thus, a complete pressing operation is impossible, 80 as the garment must be moved over for the next area to be pressed, and the pressing action each time is but partially under steam due to the momentary application of the latter. It has been my intention to overcome 85 these and other deficiencies entering into the present method of pressing portions of garments on the lines given, by the provision of a novel attachment which accomplishes the 90 objects outlined above to their fullest extent. 95

In carrying out the invention, I build the novel attachment in the nature of an abutment for the lever 10 when the buck 6 is raised. Thus, the main portion of the attachment 100 comprises a generally vertical post 12, having

- a foot 12a which is somewhat arched to seat firmly on the medial bearing sleeve 7a of the stationary shaft 7b loosely journalled in the rocker frame 7. The bearing sleeve and the shaft are usually connected on the standard machine by a set screw 13, and I replace this by one of a greater length as shown for the purpose of including the foot 12a, which is made with an open slot 12b for the passage of the screw shank. Also, the extra length of the screw permits of a lock nut 13a to be applied for the securing of the foot 12a independently of the fastening between the bearing sleeve 7a and the shaft 7b.
- 15 The post 12 rises behind the upper buck 6 to a position generally even with the same when the upper buck is in raised position, receiving a cross shaft 14 at the top, where the post is made with a head portion 12c.
- 20 Alongside the latter, the shaft 14 snugly receives in pivotal relation the head 15a of an arm 15 which extends in a forward direction over the position of the hand lever 10 terminating with a lateral bend 15b, which is directly above the handle portion of the lever. Ordinarily, the post 12 and the arm 15 are to serve as one unit and in the positions indicated in Figure 1. However, in order that the arm 15 may be relied upon to open further from the post 12, I apply a pawl 16 to a shoulder 12d of the post head 12c, using a small spring 17 to draw the pawl 16 down into engagement with the shoulder. The pawl is pivotally attached at 16a alongside the arm 15 and is extended forwardly with a lever section 16b. Thus, while the pawl is normally engaged with the head 12c to prevent the arm 15 from opening with reference to the post 12, when it is desired, the lever section 16b may be depressed to release the pawl from the shoulder and permit the arm 15 and parts carried thereby to be swung over rearwardly to a position remote from the buck 6.
- 30 40 45 50 55 60 65 66 68 69 70 75 80 85 90 95 100 105 110 115 120 125 130
- In the ordinary use of the buck 6, the limit of its rise is reached when a tail portion 6b strikes the rubber bumper 9 of the base 8. For the purpose of my invention, however, I mount the bumper 9 with a snugly fitting compression spring 18, which extends a short distance above the bumper and to such a degree that it will impart a slight rebound to the buck 6. This rebound is so calculated that with my attachment mounted, the position of the buck will be with the lever 10 immediately beneath the frontal bend 15b of the arm 15. It will now be seen that should the buck be given upward pressure, the arm 15 will impede the rise of the lever 10, so that the continued rise of the buck will result in the opening of the steam valve 11. Since under customary conditions the pressure stroke required upon the lever 10 to deliver steam is less than an inch in extent, it will be seen that the return of the buck 6 as occasioned by the

rebound spring need only be for a distance to correspond whereby to secure the automatic valve action mentioned.

In the use of my attachment, the garment may be taken up and the portion required to be pressed hung over both of the operator's hands as gathered side by side, the relatively large piece then being applied direct to the buck with pressure. As this is done, the steam issues upon the entire area of the piece, and the latter may be thus held as long as is necessary for the thorough steaming of the goods. Since the supply of the steam is automatic, the operator's hands need not change their position, but can be used fully to properly hold the garment portion against the buck and even shifted in one or the other direction to extend the area to be steamed and pressed, no regard or attention whatever being required for the control of the steam. As soon as pressure upon the buck is released, the latter is automatically depressed by the action of the rebound spring 18, permitting the steam valve to close at once, so that the time of the operation is controlled at will and without any special effort. Needless to say, since the hands of the operator are within the garment or on the side remote from the buck, no access is had by the steam to produce injury or discomfort and the garment may, therefore, be given brief pressing applications with perfect comfort to the operator.

While the attachment could perform its main purpose when made in a single piece, it is preferable for two reasons, to make it in the two pieces represented by the post 12 and the arm 15. First, the two pieces may, because of their pivoted relation, be folded for compactness and economy in shipping or handling; and second, as previously mentioned, the pawl 16 may be released to permit the arm 15 to be swung out of the way, such as when garments are to be pressed between both of the bucks and the customary use of the lever 10 is to be made. It will be realized that when both bucks are used, the steam does not issue forth freely, and the operator can with ease actuate the lever 10 while holding the buck 6 down with the handle 6a thereof.

Aside from the general construction and operation of the novel attachment, it will be seen that I have provided in the slotted foot 12a of the post 12, a simple and rapid method of applying or removing the attachment from the machine, requiring no alteration in the latter except that of replacing the customary bolt as mentioned by a longer bolt 13 and providing the same with the lock nut 13a. Below, the function of the bumper is not hampered as the same may serve as before and even with greater resiliency due to the addition of the spring 18. However, the importance of this spring is not so much in its

resiliency as in the fact that it automatically sets the upper buck in a position admitting of a further movement from its poised state. Other expedients than this added movement of the buck could doubtless be designed to 5 actuate the valve lever 10 without manual aid, but these would of necessity entail the separate attention of the operator and very likely involve working controls and even impediments. In my case, however, lending the buck a further movement enables its use 10 as a lever which is invoked by no other effort than the pressure application of the garment. The return of the buck need not originate at the site of the spring 18, as a spring or its 15 equivalent could be elsewhere applied with the same effect. However, the chosen location makes for the simplest method designed to keep the machine free of projecting parts or other complications.

20 Incidentally, the provision of the spring 18 acts to lower the poised position of the buck somewhat. Generally, the extent of this departure should be considered negligible; 25 however, where even so slight a deflection of the buck is objectionable, it is an easy matter to further sink the bumper 9 or otherwise reduce its prominence, and shorten the spring 18 accordingly, restoring the former poised height to the buck.

30 In conclusion, it will be evident that my attachment supplies by means of a simple and comparatively inexpensive structure a method of steaming garment portions more 35 thoroughly, safely and quickly than in the past.

I claim:

40 1. The combination with the movable upper buck of a pressing machine, a valve for admitting steam to the buck, and a lever carried by the buck and movable to open said valve; of a stationary abutment opposite the lever and effective to actuate the latter when the upward movement of the buck causes the 45 lever to strike and yield to the abutment.

45 2. The structure of claim 1, said abutment comprising an arm extending over the buck, and a post affixed to the frame of the machine and rising to connect with the arm.

50 3. The structure of claim 1, said abutment comprising an arm extending over the buck, a post extended from the arm to the frame of the machine, a recessed foot-projected from the post, and a clamping bolt applied 55 to the foot and passing through the recess into the frame.

4. The structure of claim 1, said abutment comprising an arm extending over the buck, and a post affixed to the frame of the machine 60 and rising to connect with the arm, the connection between the arm and the post being a break-joint to render these parts foldable.

5. The structure of claim 1, said abutment comprising an arm extending over the buck, 65 and a post affixed to the frame of the machine

and rising to make a break-joint with the arm, and means to lock the break-joint whereby to check the arm from moving away from the buck.

6. The structure of claim 1, said abutment 70 comprising an arm extending over the buck, and a post affixed to the frame of the machine and rising to make a break-joint with the arm, and means to lock the break-joint whereby to check the arm from moving away from the buck, said means comprising a spring-retainer pawl carried by the arm, and a shoulder projected from the post, the pawl seating in the shoulder and locking the arm from the movement aforesaid.

80 In testimony whereof I affix my signature.
GEORGE M. SVOJSE.
